CHARLES WAGNER

IMPRINT-TRANSFER MECHANISM

Application filed September 19, 1929. Serial No. 393,667.

This invention relates to improvements in imprint-transfer mechanism.

It is desirable to transfer imprints from the soft composition blanket cylinder to an off-set press to rolls or rollers of hard material so as to enable such hard rolls to be used for etching or printing or the like, but owing to the soft, elastic character of the composition forming such blanket, it has heretofore been difficult, if not impossible, to transfer an imprint therefrom to a roller composed of a hard material such as copper, brass, steel or stone. This is due to the fact that any variation in the pressure or spacing between the two rollers will, because of the softness and elasticity of the material of which the blanket is made, produce a distortion of the imprint of the soft, elastic surface and a consequent distortion imprint on the hard surfaced roller, and it is one of the objects of this invention to avoid this distortion of the imprint in such imprint-transfers between such soft, elastic material and a hard surfaced roller.

Another object of this invention is to produce a transfer mechanism by modifying the conventional cylinder of an offset print press so as to enable an imprint from such cylinder to be transferred to a roller of hard material such as copper, nickel, steel or stone and to enable such imprint to be obtained on the hard roller accurately and without distortion thereof.

Still another object of my invention is to enable a single offset cylinder to be utilized with blankets and hard rollers of varying widths.

Still another object of my invention is to provide on an offset cylinder a pair of spacing tracks or rails by the use of which the hard roller will be positively spaced a predetermined distance from the surface of the offset cylinder and will thus enable the two surfaces to be rotated relatively in such properly-spaced relationship as to compensate for the thickness of the blanket and to enable transfer from the blanket of imprints to such hard roller irrespective of any inaccuracies in the cylinder or roller.

Still another object of my invention is to

provide means whereby these compensating tracks or rails may be readily and quickly applied to or removed from the cylinder and also to provide means whereby the position on the cylinder of the rails may be quickly adjusted to accommodate blankets and rollers of varying widths.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:

Fig. 1 is a fragmentary view, partly in section and partly in side elevation, of a transfer mechanism embodying my invention and applied to a conventional offset press, the offset cylinder being shown in contact with the bed of the press to receive a impression or imprint therefrom;

Fig. 2 is a view similar to Fig. 1 of the transfer mechanism showing the offset cylinder raised into contact with the hard roller for the purpose of transferring the imprint thereto;

Fig. 3 is an enlarged view, in plan, of the hard and offset rollers in operative relationship to each other but dismounted from their bearings;

Fig. 4 is a still further enlarged section on the line 4-4 of Fig. 3, looking in the direction of the arrow;

Fig. 5 is a fragmentary section on the line 5-5 of Fig. 3, looking in the direction of the arrow;

Fig. 6 is a perspective view of one of the tracks, rails or bands and the adjusting and fastening mechanism therefor.

Referring now to these drawings, which illustrate a preferred embodiment of my invention, 1 indicates the frame of a conventional offset hand press and 2 the bed thereof having conventional racks 3 at opposite sides of said bed. 4 indicates bearing brackets mounted on a carriage 4' having wheels 4a running on tracks 5 and carrying an offset

cylinder 6 having journals 7, mounted in bearing blocks 8 movable vertically in ways 9 by means of screw shafts 10 threaded through yokes 11 and rotatable through arms 12 which are connected together by a connecting rod 13, a hand lever 14 being, as shown, connected to one of the arms 12.

The cylinder 6 is also provided with gears 15 at opposite sides which mesh with the racks 13 to enable the cylinder to be rotated over the bed of the press by the rotation of pinions 16 meshing with the gears 15, these pinions being, as shown, mounted on a shaft 17 journalled in suitable bearings in the bearing brackets 4. These pinions are rotated by means of a crank arm 18 to cause a movement of the carriage 4 along the bed of the press of the cylinder 6 over and in contact with the same for the purpose of obtaining an imprint on the said cylinder, which is provided with the usual blanket 19 having the conventional soft and elastic surfacing material on which, of course, an imprint is obtained from a stone, type or other inked surface on the bed of the press.

Having thus obtained the imprint on such soft and elastic composition, it is desirable to transfer the impression from this soft and elastic printing surface to a roller 25 of hard material, as for example, to an etching roller of copper or other suitable material and it has heretofore been found difficult, if not entirely impossible, to procure an accurate imprint or transfer from this soft material on the cylinder to a roller composed of hard material because it is apparent that any inequality of pressure or any change of the distance between the two rollers will, in view of the soft and elastic character of the blanket 19 on the offset cylinder, cause the transferred imprint to be distorted.

By the use of my invention, I have overcome this difficulty by providing a pair of tracks or rails, one of which is applied to the roller on each side of the offset blanket and these rails or tracks are, in the preferred form of my invention, in the form of bands 20 of a thickness adapted accurately to compensate for the thickness of the blanket and its printing composition, and equalizing the amount of pressure that may be applied on such soft printing composition or surfacing material.

In the preferred form of my invention, the bands 20 are provided with means for adjustably securing the same on the cylinder so as to enable such bands to be spaced varying distances apart and thus to enable printing blankets and hard rollers of varying widths to be used with a single cylinder. To this end, each of the bands 20 comprise a roller-encircling portion 20' and fastening arm 20^a adapted to fit into blanket-fastening grooves 6' of the cylinder 6.

In the preferred embodiment of my invention, these arms 20^a are fastened by screws 21

to a block 22 slidable along rods 23 each of which are adjustably mounted by bolts 24 screwed into tapped holes 24' in the bottom wall 6^a of the grooves 6' of the cylinder 6. Obviously, the rail or track bands 20 will be thus adjustably mounted on the cylinder so as to permit considerable variation of the distance between the two rails and consequently to enable a variation in the widths of the blankets and hard rollers with which these bands may cooperate.

Adjustment of the bands may be accomplished by a mere loosening of the bolts 24 whereupon the blocks 22 and bands secured thereto may be moved along the rods 23 to any suitable position whereupon a screwing down of the bolts 24 will secure the bands in the adjusted position to which they have been moved.

It will be obvious that when these bands are properly spaced from each other, they will form rails along which the hard surfaced roller may roll and also that if these bands are of the proper thickness to compensate for the thickness of the blanket and its printing composition, the hard surfaced roller may be rotated about the surface of the cylinder in such properly spaced relationship thereto as to provide the proper amount of pressure necessary to procure a good transfer and without any excessive pressure which might cause a dépression, flattening or creeping of the soft material and a consequent distortion of the imprint transferred.

As shown, I provide conventional means for connecting the blanket to the offset cylinder and, as illustrated, the opposite ends 19' of the blanket are rolled around and secured to fastening rods 19^a which are mounted in the groove 6'.

The roller 25 is rotatably mounted or journalled in blocks 26 slidable in ways 27 and movable by screws 28 threaded through yokes 29 and operable by a hand-wheel 30.

In the preferred form of my invention illustrated, the cylinder 6 after obtaining its imprint by a movement over the bed of the press is raised by means of the hand-lever 14 to elevate the same so that the gears carried thereby will be out of contact with the racks 3 and the surface of the blanket will be caused to contact with the hard surfaced roller 25. When this contact is established, the pinions 16 will still be in mesh with the gears 15 carried by the cylinder and rotation of the crank-arm 18 will cause the cylinder to be rotated in contact with the roller 25 and the imprint to be transferred thereto.

From the above it will be seen that I utilize a single gearing for alternately moving the cylinder over the bed of the press to procure the imprint on the blanket and for rotating the cylinder in contact with the roller 25 to transfer the imprint from the cylinder thereto.

Having thus described my invention, I claim:

1. Imprint-transfer mechanism embodying, in combination, a cylinder mounted to 5 rotate, a pair of rails mounted on said cylinder in adjustable relationship to each other, one member of each pair being arranged on each side of the middle portion of the roller, a blanket having a soft printing composition 10 mounted on said cylinder between said rails, and a transfer roller of hard material mounted to rotate adjacent to said cylinder and to contact upon rotation with said rails and with the surface of said blanket, said rails 15 having a thickness adapted to compensate for the thickness of the blanket and to equalize the pressure of said roller on the surface thereof.

2. Imprint-transfer mechanism embodying, in combination, a cylinder mounted to 20 rotate, a blanket having a relatively soft printing composition mounted on said cylinder, a pair of slideable blocks mounted on the cylinder, rails mounted on said blocks, one member 25 of each pair being arranged on each side of the blanket, and a transfer roller of hard material mounted to rotate adjacent to said cylinder and to contact upon rotation with said rails, said rails having a thickness adapted 30 to compensate for the thickness of the blanket and to equalize the pressure of said roller on the surface thereof.

3. Imprint-transfer mechanism embodying, in combination, a cylinder mounted to 35 rotate, a blanket mounted on said cylinder having a printing surface composed of relatively soft printing composition, said cylinder having a conventional blanket-fastening groove, blanket-fastening rods mounted in 40 said groove, a pair of rail-mounting rods mounted in said groove between said blanket-fastening rods, a pair of blocks slidably mounted on said rods, a pair of track bands mounted on said blocks, one member of each 45 pair of track bands being arranged at each side of the blanket, and a transfer roller of hard material mounted to rotate adjacent to said cylinder and to contact upon rotation with said rails, said track bands having a 50 thickness adapted to compensate for the thickness of the blanket and to equalize the pressure of said roller on the surface thereof.

4. Imprint-transfer mechanism embodying, in combination, a press having a flat bed, a carriage movable along said bed and provided with mounting brackets, a cylinder mounted in said brackets, a transfer roller also mounted in said brackets above said 55 cylinder, and means for alternately moving said cylinder from a position in contact with the bed of the press and out of contact with said transfer roller to a position in contact with the transfer roller and out of contact 60 with the bed of the press.

5. Imprint-transfer mechanism embodying, in combination, a press having a flat bed, a carriage movable along said bed and provided with mounting brackets, a cylinder mounted in said brackets, a transfer roller 70 also mounted in said brackets above said cylinder, means for alternately moving said cylinder from a position in contact with the bed of the press and out of contact with said transfer roller to a position in contact with 75 the transfer roller and out of contact with the bed of the press, and common means for rotating said cylinder in said alternate positions.

In witness whereof, I have signed my name 80 to the foregoing specification.

AUGUST HORMEL.
